UNITED STATES PATENT OFFICE.

GEORGE PETERSON, OF BAYONNE, NEW JERSEY, ASSIGNOR TO SUPREME OILBURNER COMPANY, OF BAYONNE, NEW JERSEY, A CORPORATION OF NEW JERSEY.

OIL BURNER.

Application filed May 16, 1927. Serial No. 191,782.

My present invention relates to an improvement in oil burners and while it is more specifically directed to that type customarily used in household heating, it need not be so limited.

Among the various advantages of my present construction, is that of simplicity of the structural parts, encompassing an improvement in the burning of liquid fuel 10 therein.

Another advantage of my structure is in the means provided for sequentially breaking up the oil, from a globular to a gaseous condition, and the further provision of 15 means whereby gas is further broken up to insure the making of an even burning flame, thereby insuring quietness in operation of the apparatus, without the usual reverberatory reaction consequent upon the burning 20 of a poorly atomized liquid fuel.

Another improvement is the use of means whereby the incoming fuel may be pre-heated by means permitting of the withdrawal of hot gases from the interior of 25 the fire pot and its introduction into the stream of ingoing liquid fuel and air, thereby to help volatilize the same.

Another advantage lies in the improvement in the means whereby a constant level 30 of fuel may be maintained within the burner proper to meet the conditions of vaporization at the predetermined level, all excess or overflow being conducted back to the source of supply.

Another advantage of my device lies in the provision of means whereby an artificial 35 oil fuel level may be created within the burner nozzle, which level is created and held only during the operation of the burner 40 but immediately recedes to the common fuel oil level when the operation of the burner is discontinued.

Owing to the foregoing conditions and the construction of the front end of the fuel 45 oil reservoir or nozzle or forward compartment thereof, as will be later described, may be utilized as a pilot light to the extent of its reserve of fuel carried therein.

These and other capabilities and advantages will be ascertained as the description 50 proceeds.

In the accompanying drawings, Fig. 1 is a sectional view indicating a fragment of a heater plant, showing my burner sys-

tem, partially in section and its associate 55 relation thereto;

Fig. 2 is a sectional view thereof from the top, taken on the line 2-2, Fig. 1, looking in the direction of the arrows;

Fig. 3 is a perspective view of the hot 60 gas inlet tube;

Fig. 4 is a perspective view of the air actuated fuel atomizing device; and

Fig. 5 is a perspective view of the lid 65 therefor shown apart from the structure in Fig. 4.

In some essentials my construction is of the well known kind, embracing, as it does, and as is indicated in Fig. 2, an electric motor 1, on one end of the shaft of which 70 is mounted any suitable fluid oil pump, such as the geared pump 2, and mounted on its opposite shaft end any suitable air blast blower 3, all of which, for the sake of cleanliness in operation, may be covered by a 75 suitable housing 4 which may be provided with an air inlet opening, not shown, for admission of air to the fan. Part of this air inlet opening is shown at 5, Fig. 1.

The blower 1, as shown herein, is of the 80 vane type, the direction of the rotation thereof being in the direction of the arrow 6, Fig. 1, and this forces the air out of the pump housing extension 7 in the direction of the arrows 8, the air being constricted at 9 85 by means of an interiorly located tapering tube 10, which is axially mounted within an outer enclosing tubular shell 11, thereby forming a graduated tapering chamber 12 therebetween.

The outer shell 11 may be developed into an enlarged cylindrical shell portion at the furnace end, and generally denoted by 13, the end 4 of which is substantially flush with the inner face of the wall of the annular fire pot 15 which is made of fire brick and suitably mounted within the boiler 16 to support the outer end of the burner mechanism just described.

Into the interior of the shell extension 13 100 is introduced a hot gas return pipe 16, Figs. 1 and 3. This pipe, it will be noted, comprises a cylindrical or tubular portion having outwardly extended foraminous flanges 17 and 18 on opposite ends thereof, the outer 105 diameters of which securely fit the inner diameter of the extension shell 13 so as to form a substantially friction-tight fit there-

with, and this shell may be suitably fastened in position by any desired means against accidental displacement.

By referring to Fig. 1, it will be noted that during the operation of the air blower the consequent air therefrom flows in the direction of the arrows 6, 8, 19, and 20, and that the air discharges from the end 'B' of the tapering tube 9, at which point, the end 'B' forms a sort of constricted orifice or venturi. The tubes 10 and 16 both cooperate to form what I shall hereinafter term a Venturi duct; and, the hot gases in returning through the annular space 20 are in constant contact with this duct even as far back as the point of contact between tube 10 and outer tube 11, thus giving an exceedingly high heat transfer efficiency to my oil burner. Just behind the front end of the venturi is located the foraminous flange 17 of the tube 16. It will be further noted that between these two, at that point, is an annular opening 19 so that by the passage of the air thereby, as indicated by the arrow 19', an eduction action is created within the chamber 20 surrounding the tube 16, and thereby draws gas from the interior of the fire pot 15, this gas entering as indicated by the arrows 21, 22 and 23, and at the Venturi point previously referred to, there joining the incoming body of fresh air, as indicated by the arrow 19', and admixing therewith, thus increasing the temperature of the incoming air and rendering it better able to take up and volatilize the fuel during the passage through the interior of the tube 16 on its way to the fire pot.

Near the end 14 of the complete burner nozzle, as described above, is located and rigidly supported an oil atomizing reservoir 40 fully shown in Fig. 4, and this comprises in its essential details a substantially rectangular container 24 divided into two compartments by a transverse wall 25, the outer or end compartment 26 having a rounded wall 27, the opposite end of the device 24 having a flat wall 28 with a threaded nipple 29 thereon, whereby to receivably hold, in operative position, a fuel oil feed pipe 30 which is amply disclosed in Fig. 1.

It will further be noted that the rounded end 27 of the reservoir 24 is stepped down as at 31, Fig. 4, and has a threaded hole 32 therein over which is mounted a draft plate 33, somewhat semicircular, in formation, and in the lid 33 is located a bore 34 into which is introduced a screw to hold the said lid in the operative position as is shown in section in Fig. 1. The plate 33 is therefore held in such a manner as to form an open gap between the reservoir 26 and the lid 33, the purpose of which will be later described.

Mounted in the rectangular chamber 35 of the fuel oil reservoir 24 and preferably transversely thereof is rotatably mounted a

bladed propeller 36, the same being supported by means of a shaft 37, simply mounted by means of a screw 38 holding the flat end of the shaft 37 in the desired axial relation to the reservoir 24. The reservoir 24 may be provided with two cut-outs 39 on opposite sides whereby the large diameter of rotative fan may be deeply immersed within the pot and, at the same time, expose a greater proportion of the fan to the air stream as indicated by the arrow 19', in Fig. 4, thus causing the fan to rotate in the direction of the arrow 40. Obviously, if the compartment 35 is partially filled to the desired level with oil, the flow of air through the inner cylinder 16 will cause the fan to rotate and the outer edges of the blade of said fan will consequently dip into the liquid oil within said reservoir and thus propel the oil therein through the opening or duct 26' in the partition 25 thereby furnishing fuel oil to the burner, the front compartment thereof 26, whereby a higher or artificial oil level than level A may be maintained in the forward compartment 26 at all times, where it is subject to the eduction action of the air stream in passing thereby and also to the heat of the fire pot. This thus provides an oil fuel supply to the ingoing heated air stream, the draft plate 33 permitting of an aspiration action by the air stream as it passes over the top thereof.

The fuel feed oil pipe 30, as indicated in Fig. 2, is run outwardly through the side walls of the tubes 10 and 11, and is threadedly joined to an oil levelizer reservoir 41 which is attached to one side of the casing 4, this levelizer being in the form of an auxiliary or separate fuel oil container, and at the point of connection of the pipe 30 with 105 41, substantially determines, as indicated in Fig. 1, the oil level A, in such reservoir.

At the opposite end of the levelizer 41 is connected an overflow pipe 42 which in turn enters into and is suitably mounted upon the main fuel oil reservoir 43 which is ordinarily buried in the ground below the level of the burner apparatus, in accord with the customary practice.

From the levelizer 41 extends another pipe 44 which is connected to the pump 2 whereby oil may be fed from the pump to the said levelizer, said oil being pumped from the main reservoir 43 through a pipe 45.

As the fuel oil is being constantly supplied by the pump 2 from the reservoir 43 to the levelizer 41 in excess quantities, it is obvious that any excess oil going above or over the level A in the reservoir 41 must flow back into the tank 43 through pipe 42 thereby maintaining the approximate level A, not only in the levelizer but also in the feed pipe 30 and in the oil atomizing reservoir 24 so that no excess oil can enter the fan reservoir thereof above the predetermined level A.

Thus it will be noted that the burner nozzle 24, by reason of its two compartments 26 and 35, is divided to maintain two fuel oil levels, one a natural feed level A, and the other a fan controlled higher level in compartment 26, and at the period of stopping or starting the burner operation the residual oil fuel in compartment 26 may be used as a pilot or starting light to ignite the fuel.

10 When the furnace is in operation, the blower forces air through the duct 10, and by the Venturi action previously described, draws hot gases from the fire pot 15, commingles these at the Venturi point B, passes 15 by and over the rotating fan 36, causing it to rotate and by reason of the ends of the vanes of the fan dipping into the oil level A, the fan throws up a higher oil level in compartment 26, which is picked up by the hot air 20 stream and advanced to the gaseous state. The oil in the chamber 26 of the reservoir nozzle 24 is practically vaporized by its proximity to the hot fire pot 15, and as the air stream passes thereby, forms a vaporous 25 fuel, creating a true gas, which burns quietly with a blue flame in the fire pot.

To further accentuate the quiet burning of the gas and to rapidly increase its temperature as it enters the fire pot, I have arranged in the path of the incoming burning fuel gas stream, a vitreous baffle C, Figs. 1 and 2, located at about the middle of the fire pot, this baffle being somewhat angular in cross-section, and presenting one of its edges 30 to the center of the fuel stream, splitting the same, and causing the gas, when the baffle becomes incandescent to burn readily and cleanly, with a minimum of smoke, odor and noise.

35 Obvious modifications may be made in the foregoing structure without departing from the spirit of novelty herein outlined or the scope of the appended claims.

Having thus described my invention, 40 what I claim is:

1. In a fuel oil burner of the class described, the combination with a source of main fuel oil supply and a fire pot, of means for operating a blast of air, and a Venturi 45 duct for carrying the air to said fire pot, a duct for conducting hot gases from the fire pot to said Venturi duct in constant contact with said Venturi duct, an oil reservoir supplied by said main supply in said Venturi 50 duct adjacent the fire pot, and means associated with said reservoir adapted to atomize the oil.

2. In a fuel oil burner of the class described, the combination with a source of 55 main fuel oil supply, and a fire pot, of means for creating a blast of air, a Venturi duct between said means for carrying air to said fire pot, a duct for conducting hot gases from the fire pot to said venturi, an oil 60 reservoir supplied from said main supply

disposed within the Venturi duct adjacent the fire pot, means associated with said reservoir to atomize the oil, and propeller means operated by said air blast associated with said reservoir to force fuel to said atomizing means at a higher head than supplied to the reservoir by the main oil supply.

3. In a fuel oil burner of the class described the combination with a source of main fuel oil supply and a fire pot of means 70 for creating a blast of air, a Venturi duct between said means for carrying the air to said fire pot, a duct for conducting hot gases from the fire pot to said venturi, an oil reservoir supplied from said main supply 75 for creating a blast of air, a Venturi duct between said means for carrying the air to said fire pot, a duct for conducting hot gases from the fire pot to said venturi, an oil reservoir supplied from said main supply 80 for creating a blast of air, a Venturi duct between said means for carrying the air to said fire pot, means associated with said reservoir to atomize the oil, means associated with said main supply for maintaining a constant supply of oil to said reservoir, and a rotatable fuel propelling fan associated with said reservoir to force the oil to the atomizing means at a head higher than that supplied to the reservoir by the main supply.

4. In a burner of the class described, a fuel burner duct comprising an outer encasing duct member, a gradual tapering air tube, means for connecting the same to a blower at one end, a hot air intake duct supported at the other end thereof and an atomizer having a perforated partition disposed adjacent the tapering tube.

5. In a burner of the class described, a fuel burner duct comprising an outer encasing shell member, a tapering air tube, means for connecting the same to a blower at one end, a hot air intake duct supported at the other end thereof and an oil spray nozzle having a perforated partition disposed 100 therein.

6. In a burner of the class described a fuel burner duct comprising an outer encasing tubular member, a tapering air tube, means for connecting the same to an air blower at one end, a hot air intake duct supported at the other end thereof, said air tube and hot air duct both cooperating to form a Venturi duct, a partitioned oil reservoir in said Venturi duct, means associated 110 with a portion of said reservoir to atomize the oil, an air actuated rotatable propeller associated with another portion of said reservoir and adapted to forcibly move oil thru said partition into said atomizing 115 portion of the reservoir.

7. In a burner of the class described, comprising, in combination with a source of main fuel oil supply, an air blower, air feeding means, a fuel nozzle therein, means for 120 feeding liquid fuel from the main source of supply to said fuel nozzle, including an auxiliary fuel receiving reservoir, said reservoir having a perforated partition therein, air driven propeller means associated with said 125

reservoir to force oil through the perforation in said partition, and means for feeding fuel from the main source of supply to said auxiliary fuel reservoir.

5. 8. In a burner of the class described comprising, in combination with a source of main fuel oil supply, an air blower, air feeding means, a rotary fuel propeller therein, means for feeding liquid fuel from the main 70 source of supply to said fuel propeller, including an auxiliary liquid fuel receiving reservoir, supporting said propeller, said reservoir having a perforated partition therein, means for feeding fuel from the 10 main source of supply to said auxiliary fuel reservoir, and means therein for maintaining a constant level of fuel in one portion of said auxiliary fuel reservoir, said propeller maintaining a higher level of fuel in an 15 other portion of said auxiliary fuel reservoir.

9. In a burner of the class described comprising, in combination with a source of main fuel oil supply, means for creating a 25 blast of air, a fire pot, a Venturi duct means therebetween, an atomizer having a perforated partition disposed within said Venturi duct, an angular vitreous baffle in said fire pot, said baffle being presented with one of its angles toward the fire pot end of said 30 Venturi duct as and for the purpose described.

10. In a fuel oil burner of the class described, a fuel atomizing nozzle comprising a 35 casing, a compartment forming wall therein dividing said nozzle into two compartments, communicating means between said compartments and an air stream actuated fuel propelling fan in one compartment adapted to force oil into the other compartment.

11. In a fuel oil burner of the class described, a fuel atomizing nozzle comprising a casing, a compartment forming wall therein dividing said nozzle into two compartments, an air stream actuated fuel propelling fan in one compartment, said wall having a duct therein for admitting fuel to the other said compartment as propelled by said fan.

12. In a fuel oil burner of the class described, a liquid fuel atomizing nozzle comprising a casing, a compartment forming wall therein dividing said nozzle into two compartments, means for conducting fuel 55 at a predetermined lower level to one compartment, said wall embodying a duct for supplying liquid fuel to the other said compartment at a higher level than in the other compartment, and rotating means in the 60 first said compartment for moving fuel from one level to the other level.

13. In a fuel oil burner of the class described, a liquid fuel atomizing nozzle comprising a casing, a compartment forming 65 partition therein dividing said nozzle into

two compartments, an air stream actuated fuel propelling fan in one compartment, means for conducting fuel at a predetermined level to the fan in said fan compartment, and said partition being provided with 70 means for passing liquid fuel, propelled by said fan, to the other said compartment at a higher level than the level in the first said compartment.

14. In a fuel oil burner of the class described, a liquid fuel supplying nozzle comprising a casing, a compartment forming wall therein dividing the said nozzle into two compartments, a rotatable fuel propelling fan in one of said compartments, means 80 for conducting fuel at a predetermined level to said fan compartment, said wall being provided with a duct to supply liquid fuel to the other said compartment at a level higher than the liquid in the said fan compartment, and means for operating said fan whereby to create said higher level.

15. In a burner, a fuel burner duct comprising an outer encasing shell member, a tapering air tube, a hot air intake duct associated therewith comprising an outer shell and an inner shell having foraminous upstanding flanges thereon, said flanges permitting engagement of the two said shells one within the other.

16. In a fuel oil burner of the class described, a liquid fuel supplying nozzle comprising a casing, a compartment forming wall therein dividing the said nozzle into two compartments, a rotatable fuel propelling fan in one of said compartments, means for conducting fuel at a predetermined level to said fan compartment, said wall being provided with a duct to supply liquid fuel to the other said compartment at a level higher than the liquid in the said fan compartment, means for operating said fan whereby to create said higher level, and a fuel spraying means on said second compartment.

17. An oil burner comprising a gradually tapering tube and a tube having a flanged foraminous portion adapted to form a Venturi duct and a blower duct for confining a mixture of heated air and air from the blower to an atomizer, said atomizer embodying spaced compartments, one of the compartments containing means for elevating the head of oil entering into the other compartment, and means associated with the atomizer for deflecting the mixture of gases into a fire chamber.

18. An oil burner, having a gradually tapering tube and a tube having a flange foraminous portion, in combination with a fire pot having a vitreous wall adapted to divide and ignite mixture of gases transmitted by the tubes, and an atomizer disposed at one terminal of the flanged foraminous tube adjacent the wall, and means

within the atomizer for elevating the head of oil therein in its travel towards the fire pot.

19. An oil burner having a gradually tapering tube and a tube having a flanged fo-
raminous portion, in combination with a fire pot embodying a vitreous deflecting wall, a jacket concentrically spaced from the fo-
raminous flanged tube, an atomizer having
10 a plurality of compartments, and means dis-
posed within one compartment for elevating
the head of oil entering into the other com-
partment.
20. In a fuel oil burner a fuel atomizer
15 comprising a casing adapted to hold oil, perforated partitioning means integral with
said casing dividing said casing into two
compartments, disc means removably asso-
ciated with one of said compartments where-
20 by an aspirating action is created on the oil
by the air stream as it passes over the top of
the disc means, an air operated rotating fluid
propeller mounted in the other compartment
and adapted to force oil into the first com-
25 partment.

21. In a fuel oil burner, a fuel atomizer comprising a casing, perforated partitioning means in said casing dividing said casing into compartments, means removably asso-
ciated with one of said compartments and 30
acting therewith as a draft member, an air
actuated fluid propeller associated with the
other compartment and supplying oil un-
der pressure to said draft portion.

22. In a fuel oil burner system, a power 35
means, an oil pump, an air blower, both
driven thereby, a fire pot, said blower and
fire pot connected by means acting as a Ven-
turi duct, atomizing means in said duct,
said oil pumping means supplying oil under 40
a constant head to said atomizing means, oil
propelling means associated with said atom-
izing means and operated by said blower to
supply oil for atomization at a head above
that supplied by the oil pumping means. 45

Signed at Bayonne in the county of Hud-
son and State of New Jersey this 13th day of
May A. D. 1927.

GEORGE PETERSON.
